UNITED STATES PATENT OFFICE.

EDGAR R. HAWLEY, OF SALT LAKE CITY, UTAH.

SPRINKLER.

1,203,542.

Specification of Letters Patent. Patented Oct. 31, 1916.

Application filed August 15, 1916. Serial No. 114,958.

To all whom it may concern:

Be it known that I, EDGAR R. HAWLEY, a citizen of the United States, and a resident of Salt Lake City, in the county of Salt Lake and State of Utah, have invented a new and Improved Sprinkler, of which the following is a full, clear, and exact description.

This invention relates to sprinkling devices and has particular reference to sprinklers for lawns or the like used in connection with a service pipe located beneath the surface of the ground.

Among the objects of the invention is to improve the construction of a sprinkler of the type indicated, in which the sprinkler head is lifted automatically by the water when turned on in the service pipe and permitted to gravitate to its closed position when the water is shut off, the sprinkler head serving as a closure for the parts connected to the service pipe.

A further object of the invention is to simplify the device with respect to its adjustability.

A still further object is to provide a sprinkler head having a strainer employed within the same.

With the above and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical sectional view of my improvement in normal closed position; Fig. 2 is a similar view, but indicating the sprinkler head elevated; Fig. 3 is a transverse sectional detail on the line 3—3 of Fig. 1; Fig. 4 is a similar view on the line 4—4 of Fig. 2; and Fig. 5 is a detail view in elevation of the spreader.

Referring now more particularly to the drawings, I show at 10 the upper end of a service pipe connection to which is secured a tubular cylindrical shell 11 with its upper end substantially flush with the surface of the ground. This shell is provided adjacent its upper end with an inwardly projecting flange 12 counterbored at its upper

surface forming a conical seat 13, into and upon which the conical spreader 14 of the sprinkler head is adapted to rest when idle. The seat 13 is depressed sufficiently to admit all of the spreader structure below or within the plane of the upper end of the shell, except the lug 15, to which a wrench or other tool may be applied for adjusting the head. It will be noted that the flare of the seat 13 corresponds to that of the conical portion 65 of the spreader 14.

The sprinkler head comprises two principal parts relatively adjustable one on the other. These parts consist of a sleeve 16 and the spreader 14, together with the shank 70 connecting the spreader to the sleeve. The sleeve is cylindrical in form throughout its length, except at its lower end where it is provided with an outwardly projecting flange 17. The main portion of the sleeve 75 is fitted to slide vertically in the central opening formed through the flange 12 of the shell, but the upper surface of the flange 17 is ground so as to fit snugly against the correspondingly ground surface 18 of the flange 12 when the head is elevated, making 80 a watertight joint. The interior of the sleeve is screw threaded at 16' for coöperation with the split thimble 19, the two parts of which are carried by the spring legs 20 85 of the shank 21 extending downwardly from the center of the spreader. The thimble is externally threaded to coöperate with the threads 16' of the sleeve, and the legs 20 are such that their inherent tendency is to 90 spread apart, causing the two parts of the thimble to engage with sufficient friction upon the inner surface of the sleeve to hold the parts from accidental relative endwise movement. The upper end of the sleeve is provided with a conical seat 22, the inclination, however, of which is less from the vertical than the inclination of the spreader 14 which coöperates with it to provide a restricted outlet for the water being distributed. In other words, the two surfaces being 95 differently inclined provide a nozzle like action which serves to increase the effectiveness of the sprinkler in practice.

At 23 I show a reticulated member constituting a strainer inserted into the lower end of the thimble 19 and held between the two parts thereof. The strainer serves to prevent large particles of sand, gravel or the like from passing outwardly and ob-

structing the restricted passageway between the upper end of the sleeve and the spreader. The spreader may easily be removed for any purpose or may be adjusted up or down in 5 the sleeve by the application of a wrench or the like to the lug 15. The sleeve is prevented from rotation in the shell by means of a fin 24 extending into a notch 25 formed in the flange 17 at the lower end of the 10 sleeve.

With the structure shown and described herein and arranged as shown in Fig. 1, when the water is turned on in the service pipe, the head will be lifted bodily so as to 15 occupy the position shown in Fig. 2. At this time the water will be forced upwardly through the sleeve past the legs 20 and spreader shank 21 and out through the restricted regulatable passageway between the 20 spreader and the upper end of the sleeve. The size of this opening will be dependent upon the force of the water, the distance it is to be projected and the amount of water 25 to be delivered in any given time. When the water is shut off in the service pipe, the sprinkler head will drop by gravity to the position shown in Fig. 1, where it will be a positive closure for the shell 11 and being below the surface of the lawn will permit

the free passage thereover of the mower or 30 other traffic.

I claim:

In a sprinkler of the character set forth, the combination of a fixed shell having a countersunk seat of conical form at its upper end, a sleeve of cylindrical form slidable up and down through said seat and having an outwardly projecting flange at its lower end, serving to make a watertight joint with the seat portion of the shell when the sleeve 40 is elevated, the interior surface of the sleeve being screw threaded, and a spreader carried by the sleeve and including a conical upper end adjustably related to the upper end of the sleeve to vary the water outlet, 45 said spreader also including a split thimble externally threaded to coöperate with the screw threads of the sleeve, the upper end of the sleeve being counterbored with a smaller angle of departure from the vertical than 50 the inclination of the spreader coöoperating therewith, and a strainer carried by the thimble and serving to prevent coarse particles from entering and clogging the restricted passageway provided between the 55 thimble and the spreader.

EDGAR R. HAWLEY.
